LAUNDRY IRON

James Seldon Baker, Sydney, Australia, assignor
to The Mantle Lamp Company of America,
Chicago, Ill., a corporation of Illinois

Application July 15, 1937, Serial No. 153,809
In Australia July 17, 1936

10 Claims. (Cl. 158—23.2)

This invention relates to laundry irons whose construction is such that they are adapted to be heated by utilizing kerosene or liquid fuel of similar character.

5 Heretofore laundry irons have been designed for use with highly inflammable liquid fuels, the utilization of such fuels being dangerous. In such irons it was not possible, however, to utilize for heating purposes kerosene or fuel of similar character.

Furthermore, in laundry irons at present known a stand is required upon which to rest the heated iron when the latter is not in use.

15 According to the invention a laundry iron is provided in which kerosene or like heavy liquid fuels can be utilized for heating purposes, the said iron being also designed to be readily handled by a user thereof. No rest stand for the iron is required. Such iron can be easily heated, and it 20 may be placed in vertical position when it is desired to impart heat to it in the first instance, or when the user may desire to do so during ironing operations. Proper heating of the iron can also be safely and readily regulated. Further, the 25 upper portion of the iron, especially the handle portion thereof, is always kept cool to prevent undue inconvenience to a user. Again, the iron is also far more economical in use than irons of known construction in which liquid fuel is utilized 30 for the heating thereof.

Referring to the accompanying drawings in which the invention is illustrated, Fig. 1 is a perspective view of one construction of a laundry iron in accordance with the invention; Fig. 2 is 35 a central longitudinal sectional elevation thereof; Fig. 3 is a view of the iron showing its top cover removed therefrom; Fig. 4 is a sectional elevation on plane 4—4 of Fig. 1; Fig. 5 is a sectional detail view of the fuel supply pipe in relation to the 40 liquid fuel reservoir; Fig. 6 is a perspective view showing the interior of one form of sole plate for the iron; Fig. 7 is a cross-sectional elevation on line 7—7 of Fig. 4; Fig. 8 is a perspective view (partly in section) illustrating the 45 iron disposed in vertical position; Fig. 9 is a sectional detail view to an enlarged scale of the cooperative end of the pump chamber and the filler cap relative to the liquid fuel reservoir of the iron; Fig. 10 is a longitudinal sectional view to an 50 enlarged scale of valve liquid fuel supplier and burner nipple associated therewith; Fig. 11 is a cross-sectional view of said valve and its casing on line 11—11 of Fig. 10; Fig. 12 is a perspective view of another construction of the laundry iron; Fig. 13 is an approximate central longitudinal 55

sectional elevation thereof; Fig. 14 is a sectional elevation on plane 14—14 of Fig. 12; Fig. 15 is a sectional elevation on line 15—15 of Fig. 13; Fig. 16 is a perspective view showing the interior of another form of sole plate for the iron; Fig. 17 is a perspective view of the iron in vertical position with the sole plate thereof removed therefrom; Fig. 18 is a cross-sectional elevation on line 18—18 of Fig. 14; and Fig. 19 is a sectional detail view of the nipple burner and valve control.

With reference to Figs. 1 to 11 in which similar numerals refer to similar parts, the iron shown therein has a sole plate 2 which is hollowed internally and furnished on its internal surface with a plurality of pin fins 3, which are staggered and vertically disposed in relation to such surface for heat distribution purposes in relation to the outer or ironing surface of the said plate 2. Sole plate 2 has also an anti-hot spot 4, same having a ramp 5 utilized as a flame spreader. Upon the sole plate 2 is mounted a partition plate 7 by the screws 8; the latter also serve to secure the bridge piece 9 to the sole plate 2. The peripheral edges of the partition plate 7 preferably correspond to that of the sole plate 2 and such plate is spaced upwardly therefrom to form a gap 11 at such edges through which heated gases from the iron can escape to atmosphere. The bridge piece 9 has secured to it by screws 13 a dome-shaped cover 12 whose peripheral edges correspond to that of the sole plate 2; screws 13 also serve for fastening the bracket 14 to the bridge piece 9. Bracket 14 supports a hollow heat non-conductive handle 15 in which can be accommodated a pump barrel 16 (Fig. 2). One end of the pump barrel 16 is rigidly secured to a liquid fuel reservoir 18, while the other end thereof is fitted with a clamping nut 19 to allow the pump barrel 16 and handle 15 to be firmly fastened to the bracket 14 and also to allow the reservoir 18 to be supported on said barrel and handle.

Reservoir 18 is furnished with a removable filler cap 20 secured to the reservoir 18 by screw sleeve 21 (Fig. 9); reservoir 18 also has an air conduction pipe 22 closable by a ball valve 23 located within an adjustable screwable cap 24 furnished with a passage 25 to outer air. The inner end of the air conduction pipe 22 extends into an extension of the rear end of the pump barrel 16 in open communication with the reservoir 18, (Fig. 9), whereby when the iron is placed in vertical position (Fig. 8), and if the ball valve 23 is off its seating, liquid fuel cannot escape from the reservoir 18.

In the pump barrel 16 and at its rear end in communication with the reservoir 18 is a non-return valve 27; a plunger 28 is also disposed in said barrel and is associated with one end of a plunger rod 30, the opposite end of the latter being furnished with a hand grip 29 located exteriorly of the barrel 16. With the hand grip 29 is associated arm 31 adapted to pass through a slot 32 in the end cap 33 of the pump barrel 16, the cap 33 having a bearing 34 for the plunger rod 30. During ironing operations the plunger rod 30 when not required can be pushed inwardly and given a quarter turn whereby such rod by such movements will be retained within the barrel 16 through the arm 31 being placed out of alignment with the slot 32. Located in the bottom of the reservoir 18 is a nipple 40 the open mouth of which within such reservoir is furnished with a gauze strainer 35 (Fig. 5). Connected to the other end of the nipple 40 is one end of a coiled liquid fuel feed pipe 36 the other end of which is connected to the tube 37 (Figs. 3, 4 and 10) the latter being located between the partition 7 and the interior 25 of the sole plate 2. Tube 37 is provided with a valve seating 41 to receive a manually operable valve 38 (Fig. 10) formed on a stem 39, whereby supply of liquid fuel from the reservoir 18 for use in heating the iron may be cut off. The stem 39 has a needle 44 which forms a cleaner for the fuel passage 45 of the nipple 42 which is carried by the tube 37. Stem 39 fits snugly within the tube 37 and can be D-shaped in cross-section (Fig. 11) whereby a very narrow fuel passage 46 will be provided between the valve stem 39 and the tube 37. Liquid fuel which passes along such passage 46 is quickly vaporized. Such valve stem 39 at its other end is loosely connected at 49 to a screw-threaded rod 48 which has a turnable knob 50 and is adapted to pass through a packing gland 51 securable to the tube 37.

Tube 37 with its nipple 42 enters a mixing chamber 53 (Fig. 4) within the cover 12, an air inlet 54 being in communication with such chamber and located in said cover. Associated with the chamber 53 is one end of a tube 55 which is coiled in any suitable manner and to the other end of which the rose burner 56 is connected. Burner 56 passes through an opening in the partition 7 and is located over the tube 37 and the ramp 5 of the anti-hot spot 4. Flame from the burner 56 is thus enabled to impinge upon the tube 37 whereby fuel in such tube can be readily vaporized. To increase heating effect 55 of such flame on the tube 37 baffle means 58 can if desired be formed integrally with the inner surface of the sole plate 2 (Fig. 6).

Affixed to the partition plate 7 and located between said plate and the sole plate 2 of the iron is a cup 60 which can be furnished with a spout 61 adapted to extend slightly beyond the peripheral edge of the cover 12. When the iron is placed in vertical position (Fig. 8) the cup 60 can be charged with say methylated spirits, which on being ignited flame therefrom will impinge against and along the tube 37 thereby heating such tube. During such heating of the tube 37 emission of air from the reservoir 18 through the pipe 22 is prevented by placing the ball valve 23 in closed relation to its seating, this being accomplished by operating the screwable cap 24. Plunger 30 can then be turned so that the arm 31 will be placed in alignment with the slot 32 and subsequently withdrawn from the barrel 16 and reciprocated whereby through such

reciprocation air from the barrel 16 will be forced through the casing of the non-return valve 27 into the reservoir 18, thereby forcing liquid fuel from said reservoir 18 into the tube 37. Liquid within the tube 37 will be vaporized before it passes through the nipple 42.

Gas from the nipple 42 enters the mixing chamber 53 wherein it is mixed with air entering thereinto through the air inlet 54 in the cover 12. Such combustible gas mixture passes through the tube 55 to the rose burner 56; flames from the cup 60 will preheat liquid fuel admitted to the tube 37 and will also ignite gas issuing from such burner 56. When the methylated spirits in the cup 60 become exhausted, flame from the burner 56 will keep the tube 37 heated. Flame from the burner 56 also impinges against the ramp 5 of the anti-hot spot 4 and is thereby spread with the result that the sole plate 2 of the iron is heated. To extinguish the flame from the burner 56 the air conduction pipe 22 is made open to atmosphere by operating the screw cap 24, thereby allowing compressed air in the reservoir 18 to escape therefrom. To prevent liquid from the reservoir 18 escaping through the nipple 42 the knob 50 is operated whereby the valve 38 will be placed on its seating 41.

The cover 12 can be furnished with an opening 57 adapted to register with a similar opening 59 in the partition 7; both openings 57 and 30 59 are arranged in alignment with the rose burner 56, whereby requisite adjustment can be made of the flame from the burner 56 through observations for this purpose made through the openings 57 and 59.

Referring to Figs. 12 to 19, in which another construction of laundry iron in accordance with the invention is shown, similar parts of the iron as hereinbefore described bear similar reference numerals, and other parts bear other reference numerals as hereinafter referred to.

The iron consists of a sole plate 62, which is hollowed internally and its internal surface is furnished with staggered vertically disposed heat spreader fins 63 (Fig. 16) for distribution of heat 45 throughout the sole plate 62. To the lugs 64 of the sole plate 62 can be attached by screws 65 a dome-shaped cover 66 the peripheral edges of which can be shaped to correspond with that of the sole plate 62, but spaced upwardly therefrom to form a gap 67 through which heated gases may escape from the iron to atmosphere. Such cover 66 is provided with a bottom plate 68 which forms a partition having openings 70 (Fig. 17) through which lugs 64 on the sole 55 plate 62 can pass; partition 68 is loosely affixed to the cover 66. The cover 66 has a plurality of vents 72 therein to permit escape of heated air from the space between the cover 66 and the partition plate 68.

Cover 66 is attachable by the screws 13 to a bracket 14; the latter supports the handle 15 containing the pump barrel which communicates with the reservoir 18 as described above-mentioned in connection with the construction 65 of iron shown in Figs. 1 to 11 of the drawings.

Secured to the reservoir 18 is a liquid fuel feed pipe 74, the open mouth of which is provided with a filter gauze 75, and is situated above the shallow well 73 located in the bottom of the reservoir 18; said pipe 74 extends between the sole plate 62 and the partition plate 68. Pipe 74 is provided with a pair of coils 76 and 77. Coil 76 is placed at right angles to the coil 77 and both said coils are disposed in close proximity to one 75

another. The coil 76 is horizontally disposed and the other coil 77 is vertically disposed; coil 77 is furnished with a tubular extension 78. Affixed to the extension 78 is a tubular chamber 79 provided with a passage 81 communicating with the extension 78 having a valve seating 83 (Fig. 18) with which is adapted to engage a valve 84, whereby passage of liquid or vaporized fuel to said extension 78 can be cut-off. The valve 84 is controlled by the hand operable milled head 85. Affixed to the tubular chamber 79 is a gas nipple 87, the latter being located within a pocket 88 formed in the cover plate 66 to which atmospheric air has access.

With the gas nipple 87 can be associated a cleaning needle 90 which is slidably mounted within the tubular chamber 79. Such needle 90 is adapted to be used for cleaning the gas nipple passage 91; such needle 90 may be manually operated by a crank pin 92 working in the slot 93 of the block 94, said crank pin 92 being affixed to a disc 95 on the end of the rotatable rod 96 which has an operating handle 97.

Rigidly secured within the cylindrical space of the vertically disposed coil 77 are a plurality of horizontally and radially disposed fins 98. One of the ends of such fins 98 is juxtaposed to the restricted end of a horizontally disposed truncated flue 100. Facing the other end of the flue 100 is a cup 101 with radially disposed fins 102 for accelerating vaporization of the liquid fuel and for spreading flame therefrom to allow such flame to have better exposure to air before it enters the flue 100. Such cup 101 is formed in the wall of the liquid fuel reservoir 18. When the iron is placed in vertical position (Fig. 17) the cup 101 is charged with methylated spirits which is lighted and the flame therefrom passes upwardly through the flue 100 and impinges against the vertically disposed coil 77 and the fins 98 attached thereto whereby the liquid fuel in the coil 77 will be vaporized.

The horizontally disposed coil 76 has affixed thereto a flame spreader 103 which is slightly conical in shape.

Between the flue 100 and the cup 101 is located a shutter 105 the latter being pivotally mounted on the cover 66, whereby when the iron is in use entry of cold air to the flue 100 will be prevented and coming into contact with the vertically disposed coil 77. The gas nipple 87 in the pocket 88 is juxtaposed to the open mouth of a mixing tube 107. The latter tube is coiled and located between the partition 68 and the cover 66. The exit opening of such mixing tube 107 has connected thereto a rose burner 108; such burner 108 protrudes through an opening 109 in the partition 68 and is located centrally of the horizontally disposed coil 76 whereby flame from the burner 108 may impinge against the horizontally disposed coil 76 and the flame spreader 103 thereby maintaining vaporization of liquid fuel in the coil 76. The flame spreader 103 prevents a hot-spot in the centre of the sole plate 62. A flame deflector and screen 110 is associated with the burner 108.

The flame from the burner 108 impinges against the inner surface of the sole plate 62 of the iron as well as the fins 63 thereof, whereby said sole plate 62 is heated. Otherwise the modified construction of iron is operated in similar manner to the iron described hereinbefore in reference to Figs. 1 to 11 of the drawings.

What I claim as my invention and desire to secure by Letters Patent is:

1. A laundry iron including in combination a sole plate, a liquid-fuel reservoir supported at one end of and spaced from said sole plate, a delivery tube extending from said reservoir and above said sole plate, and a preheating cup having its axis substantially parallel with and above said sole plate and opening towards said delivery tube, whereby with said sole plate in vertical position the flame from preheating material in said cup will heat said delivery tube.

2. A laundry iron including in combination a sole plate, a liquid-fuel reservoir, and a circular burner substantially smaller than the width of said sole plate and supplied with fuel from said reservoir and discharging towards said sole plate, said sole plate having a substantially thickened portion in the path of flame from said burner, whereby the heat conductivity of the portion of the sole plate directly impinged upon by flame from said burner is substantially less than the heat conductivity of other portions of said sole plate.

3. A laundry iron including in combination a sole plate, a liquid-fuel reservoir, a circular burner substantially smaller than the width of said sole plate and supplied with fuel from said reservoir and discharging towards said sole plate, said sole plate having a substantially thickened portion in the path of flame from said burner, and a delivery tube extending from said reservoir to said burner, said thickened portion having a ramp face directed towards said delivery tube, whereby the heat conductivity of the portion of the sole plate directly impinged upon by flame from said burner is substantially less than the heat conductivity of other portions of said sole plate.

4. A laundry iron including in combination a sole plate, a liquid-fuel reservoir supported at one end of and spaced from said sole plate, a delivery tube extending from said reservoir and above said sole plate, and a preheating cup having its axis substantially parallel with and above said sole plate and opening towards said delivery tube, whereby with said sole plate in vertical position the flame from preheating material in said cup will heat said delivery tube, said delivery tube including a pair of juxtaposed coils disposed in horizontal and vertical positions respectively and in the path of flame from said preheating material.

5. A laundry iron including in combination a sole plate, a liquid-fuel reservoir supported at one end of and spaced from said sole plate, a delivery tube extending from said reservoir and above said sole plate, a preheating cup having its axis substantially parallel with and above said sole plate and opening towards said delivery tube, whereby with said sole plate in vertical position the flame from preheating material in said cup will heat said delivery tube, a burner supplied with fuel by said delivery tube and discharging towards said sole plate, said delivery tube including a pair of juxtaposed coils disposed in horizontal and vertical positions respectively and in the path of flame from said preheating material, and a spreader carried by said horizontally disposed coil in the path of discharge from said burner.

6. A laundry iron including in combination a sole plate, a liquid-fuel reservoir supported at one end of and spaced from said sole plate, a delivery tube extending from said reservoir and above said sole plate, a preheating cup having its axis substantially parallel with and above said

sole plate and opening towards said delivery tube, whereby with said sole plate in vertical position the flame from preheating material in said cup will heat said delivery tube, said delivery tube including a pair of juxtaposed coils disposed in horizontal and vertical positions respectively and in the path of flame from said preheating material, a plurality of horizontally and radially disposed heat-radiating fins in said vertical coil, an open-ended cone-shaped flue in line with said fins, and a movable shutter for controlling gas flow through said flue.

7. A laundry iron including in combination a sole plate, a liquid-fuel reservoir supported at one end of and spaced from said sole plate, a delivery tube extending from said reservoir and above said sole plate, valve means connected with said delivery tube, said delivery tube including a pair of juxtaposed coils disposed in horizontal and vertical positions respectively, a tubular extension connected with the outlet end of said vertical coil and having a valve seat adjacent said outlet end, said valve means including an adjustable valve cooperating with said valve seat to control fuel flow from said vertical coil into said tubular extension, a tubular chamber in open communication with said tubular extension, and an apertured nipple in an end wall of said tubular chamber and controlling fuel flow therefrom.

8. A laundry iron including in combination a sole plate, a liquid-fuel reservoir supported at one end of and spaced from said sole plate, a delivery tube extending from said reservoir and above said sole plate, valve means connected with said delivery tube, said delivery tube including a pair of juxtaposed coils disposed in horizontal and vertical positions respectively, a tubular extension connected with the outlet end of said vertical coil and having a valve seat adjacent

said outlet end, said valve means including an adjustable valve cooperating with said valve seat to control fuel flow from said vertical coil into said tubular extension, a tubular chamber in open communication with said tubular extension, an aperture nipple in an end wall of said tubular chamber and controlling fuel flow therefrom, a block movable longitudinally in said tubular chamber, a needle carried by said block in line with said nipple aperture, a crank engaging said block, and an operating rod extending from said crank through a wall of said chamber for external operation to clean said nipple by movement of said needle by said crank into said nipple aperture.

9. In a laundry iron, the combination of a sole plate, a burner for projecting combustible mixture towards said sole plate, said sole plate having a horizontal active position and a vertical inactive position with said burner in operation, and a preheating cup adjacent the lower end of said sole plate and opening upwardly for the inactive position of said sole plate.

10. A laundry iron including in combination a sole plate, a liquid-fuel reservoir supported at one end of and spaced from said sole plate, a delivery tube extending from said reservoir and above said sole plate, and a preheating cup having its axis substantially parallel with and above said sole plate and opening towards said delivery tube, said preheating cup being adjacent the reservoir end of said delivery tube, whereby with said sole plate in vertical position and in preheating said delivery tube the outlet portion thereof is spaced a substantial distance above said preheating cup and in the highly heated zone of action of burning fuel in said preheating cup.

JAMES SELDON BAKER. 10
